(57) CLAIM

The ornamental design for a louver, as shown and described.

DESCRIPTION

FIG. 1 is a perspective view of a first embodiment of a louver showing my new design;

FIG. 2 is a front elevation view of the louver shown in FIG. 1;

FIG. 3 is a rear elevation view of the louver shown in FIG. 1;

FIG. 4 is a top plan view of the louver shown in FIG. 1;

FIG. 5 is a bottom plan view of the louver shown in FIG. 1;

FIG. 6 is a first side elevation view of the louver shown in FIG. 1;

FIG. 7 is a second side elevation view of the louver shown in FIG. 1;

FIG. 8 is a perspective view of a second embodiment of a louver showing my new design;

FIG. 9 is a front elevation view of the louver shown in FIG. 8;

FIG. 10 is a rear elevation view of the louver shown in FIG. 8;

FIG. 11 is a top plan view of the louver shown in FIG. 8;

FIG. 12 is a bottom plan view of the louver shown in FIG. 8;

FIG. 13 is a first side elevation view of the louver shown in FIG. 8; and,

FIG. 14 is a second side elevation view of the louver shown in FIG. 8.

The broken lines illustrate portions of the louver that form no part of the claimed design. Furthermore, the louver is shown with a symbolic break in its length. The appearance of any portion of the louver between the break lines forms no part of the claimed design.

1 Claim, 10 Drawing Sheets
